Primary Examiner — Darlington Ly*(74) Attorney, Agent, or Firm* — Michael Best & Friedrich LLP**CLAIM**

We claim the ornamental design for a [round] tray, as shown and described.

DESCRIPTION

FIG. 1 is an isometric view of the claimed design from the top, right side, and front side thereof;
FIG. 2 is a top plan view thereof;
FIG. 3 is bottom plan view thereof;
FIG. 4 is front side view thereof;
FIG. 5 is a back side view thereof;
FIG. 6 is a left side view thereof;
FIG. 7 is a right side view thereof;
FIG. 8 is a first cross-sectional view thereof taken along line 8-8 in FIG. 2;
FIG. 9 is a second cross-sectional view thereof taken along line 9-9 in FIG. 2;
FIG. 10 is a third cross-sectional view thereof taken along line 10-10 in FIG. 2;
FIG. 11 is a fourth cross-sectional view thereof taken along line 11-11 in FIG. 2; and,
FIG. 12 is a fifth cross-sectional view thereof taken along line 12-12 in FIG. 2.

The broken lines having equal length segments shown in the drawings illustrate portions of the tray that form no part of the claimed design. The broken lines having unequal length segments illustrate the boundary of the claimed design and form no part of the claimed design.

1 Claim, 8 Drawing Sheets

Matter enclosed in heavy brackets [ ] appears in the original patent but forms no part of this reissue; matter printed in italics indicates the additions made by reissue.
